CLAIM

The ornamental design for a cardiac pacemaker tester, as shown and described.

DESCRIPTION

FIG. 1 is a top and left front perspective view of a cardiac pacemaker tester showing my new design;

FIG. 2 is a top plan view thereof;

FIG. 3 is a left side elevational view thereof, the right side being a mirror image thereto;

FIG. 4 is a bottom plan view thereof;

FIG. 5 is a rear elevational view thereof; and

FIG. 6 is a front elevational view thereof.

FIG.1
